SLIDING ABUTMENT UNIT FOR ROTARY
DISPLACEMENT PUMPS OR MOTORS

Hugh Jeffries, Santa Monica, Calif.

Application August 12, 1943, Serial No. 498,372

2 Claims. (Cl. 103—123)

1

My invention relates to improvements in sliding abutment units for rotary displacement pumps, or motors, the principal object in view being to provide an efficient mechanical unit designed for the purpose of converting and transmitting rotary power hydraulically.

Another object of the present invention is to provide a unit of the character stated wherein the volume of fluid in the system in which the unit is installed is constant and under positive confinement.

Another important object of the invention is to provide a unit of the character stated which when installed in a hydraulic system will promote the flow of fluid in the system at a constant rate regardless of the speed of flow.

Other objects and advantages of the invention will become apparent to the reader of the following description.

In the drawings:

Figure 1 is a side elevational view of the unit.

Figure 2 is a transverse section on the line 2—2 of Figure 1.

Figure 3 is a perspective view of one of the sliding abutments.

Figure 4 is a section on the line 4—4 of Figure 2.

Figure 5 is a vertical sectional view through a slightly modified form of the invention showing a slightly modified form of sliding abutment.

Figure 6 is a top plan view of the structure shown in Figure 5.

Referring to the drawings wherein like numerals designate like parts, it can be seen that numeral 5 generally refers to a stator which consists of an annulus 6 having a base 7 and side walls 8, 9, from which rise plates 10 which define end walls for a vertical block formation 11 on the annulus 6.

A partition 12 is provided between the side walls 8, 9 and this at its upper end also has a portion 13 rising to the top level of the plates 10 and this carries an inverted U-shaped conduit 14, the leg portions of which define cylinders 15, 15 in which operate pistons 16, 16 on a pair of abutments 17, 18. At this point, it can be seen that the plate formations 10 on the side walls 8, 9 are secured by machine screws 19 to the block 11.

The abutments 17, 18 are constructed as substantially shown in Figure 3, each consisting of the gate portion 20 and a riser 21 extending upwardly therefrom and carrying the piston 16, and a pair of guide legs 22, 22 which move in guideways 23, 23 at opposite sides of the corresponding cylinder 15 of the conduit 14.

Numerals 24 denotes a rotor located within the stator and this of the two-part construction consisting of a rotor element 25 operative in the chamber at one side of the partition 12 and a

rotor element 26 operative in the chamber at the opposite side of the partition 13. These rotor elements may be individual and splined as at 27 to the shaft 28, or they may be integral.

It can be seen, that the rotors are substantially circular, but eccentrically mounted on the shaft 28 so that the peripheral portion thereof furthest removed from the shaft 28 constantly wipes the inside of the stator 6. Further, the elements 25, 26 of the rotor are oppositely disposed, in other words, when the rotor element 26 has forced its sliding abutment to its uppermost position, the sliding abutment in the other compartment is at its lowermost position, and this is clearly shown in Figure 2.

A small cylinder 30 rises from the conduit 14 and has a cap 31 through which a screw 32 is feedable and this screw has a piston 33 on its lower end. Obviously, this serves to take up any lost motion in the movement of the fluid 34 in the conduit 14.

The unit is installed in a system, numeral 34 denoting a return pipe, while numeral 35 denotes a distribution pipe. The return pipe 34 has branch pipes 36 which are secured as at 37 to the side walls 8, 9 and communicates with intake openings 38 at one side of each of the sliding abutments 17, 18, while the distribution pipe 35 has branch pipes 39 which are secured as at 40 to the side walls 8, 9 over outlet openings 41 at the remaining sides of the sliding abutments 17 and 18.

The action of the gates 17, 18 is reciprocal. In following the contour of an element of the rotor, one gate valve is caused to rise while the other gate is correspondingly forced downwardly, following the contour of the companion rotor element, and this is accomplished by means of the fluid confined in the synchronizing conduit 14.

Obviously, in the operation of the unit the same is reversible with rotary power applied to the axle, it is a pump. With fluid supplied as a pressure it is a motor. In operation the fluid enters the ports 38 and is forced around in the corresponding chamber of the stator, by the corresponding rotor element, to the outlet openings 41, and this action on the fluid is constant and not intermittent.

As will be discerned from an examination of the drawings, particularly Figures 4 and 5, the rotors are not only eccentrically mounted in the stator, but are arranged with respect to each other so that their greatest radial measurements are located in opposite directions, this having the effect that for the entire peripheries of these rotors the displacement is exactly complementary and equal to the displacement constant for which the unit is designed.

A slightly modified form of gate is shown in Figure 5, wherein the reference character 5a

denotes a stator including an annulus 6a and the interior is divided by a partition 12a at each side of which operates a rotor element 25a. The side walls of the stator have inlet and outlet ports 38a, 41a between which operate arcuate-shaped sliding abutments 17a, each of which has an arm 50 pivotally mounted in a conduit 14a in which is a volume of fluid and which functions substantially as does the conduit 14 with the fluid 34 therein in the form of the invention shown in Figure 2.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A hydraulic unit of the character described comprising a stator, a rotor mounted in the stator, said stator being divided into a pair of chambers, said rotor being divided into a pair of rotor elements, a shaft, said rotor elements being eccentrically mounted on the shaft and having their greatest radial measurements located in opposite direction, a sliding abutment in each of the chambers having continuous contact with the periphery of its respective rotor element, each chamber having an inlet port at one side of its sliding abutment and an outlet port at the opposite side of its sliding abutment, and equalizing means consisting of an arched conduit containing a volume of fluid and having opposite ends extending into said chambers, and a piston on each of the sliding abutments operative in one end of the conduit.

2. A hydraulic unit of the character described comprising a stator, a rotor mounted in the stator, a partition in said stator dividing the same into a pair of chambers, said rotor being divided

ed into a pair of rotor elements, a shaft, said rotor elements being eccentrically mounted on the shaft and having their greatest radial measurements located in opposite direction, a sliding abutment in each of the chambers with which the periphery of one of the rotor elements is operatively engaged, each chamber having an inlet port at one side of its sliding abutment and an outlet port at the opposite side of its sliding abutment, and equalizing means consisting of a vertical U-shaped conduit straddling said partition with ends opening into said chambers, said conduit containing a volume of fluid, and a piston on each of the sliding abutments operative in the corresponding end of the conduit, each of said sliding abutments being provided with a pair of guide legs upon opposite sides of the piston thereof, said stator being provided with guideways for said guide legs.

HUGH JEFFRIES.
